LEENDERT PIETER POLHUIS, OF AMSTERDAM, NETHERLANDS, ASSIGNOR TO REMINGTON TYPEWRITER COMPANY, OF ILION, NEW YORK, A CORPORATION OF NEW YORK.

TYPE-WRITING AND COMPUTING MACHINE.

1,147,431.

Specification of Letters Patent.

Patented July 20, 1915.

Application filed April 30, 1913. Serial No. 764,635.

To all whom it may concern:

Be it known that I, LEENDERT PIETER POLHUIS, a subject of the Queen of the Netherlands, and resident of Amsterdam, in the Province of Noord, the Netherlands, have invented certain new and useful Improvements in Type-Writing and Computing Machines, of which the following is a specification.

10 My invention relates to computing machines and especially to combined typewriting and computing machines.

My invention has for its principal object to provide improved means for crossfooting, that is to say, for adding together numbers written in a line across the paper.

Another object of my invention is to convert the Wahl computing mechanism when combined with typewriting mechanism into 20 a crossfooting machine by means involving a minimum of modification of said Wahl mechanism and of the typewriting mechanism.

Another object is to provide means whereby the traveling element of the computer can be mounted so as to be adjustable to any desired position relative to the carriage travel, and so that such adjustment will be brought about by tabulator mechanism and 30 so that its said position will be determined by the adjustment of the tabulator column stop.

To the above and other ends which will hereinafter appear, my invention consists in 35 certain features of construction and combinations and arrangements of parts, all of which will be fully set forth herein and particularly pointed out in the claims.

In the accompanying drawings, Figure 1 is a left-hand side elevation of a combined typewriting and computing machine with parts thereof shown in section or broken away and with parts omitted. Fig. 2 is a front elevation of the same. Fig. 3 is 45 a fragmentary left-hand side elevation, partly broken away and partly in fore and aft vertical section, of some of the mechanism. Fig. 4 is a fragmentary top plan view of the same, with parts broken away 50 and parts in section. Fig. 5 is a fragmentary

view of a portion of Fig. 3 but with the parts in different positions. Figs. 3, 4 and 5 are on a larger scale than Figs. 1 and 2.

My invention is applicable or adaptable to typewriting and computing machines generally, but I have here shown it applied to a Remington-Wahl machine. This combination, consisting of a Wahl computer mounted as an attachment on a Remington No. 11 typewriter, is extensively manufactured, 55 sold and used; and much of the mechanism shown in the drawings is identical with this manufactured and marketed combination.

The Remington No. 11 typewriter has a stationary framework comprising a base 65 part 1, corner posts 2 and top plate 3, on which last are mounted a front stationary carriage rail 4 and a rear stationary carriage rail 5 between which is mounted a traveling paper carriage 6 supported by grooved rails 70 respectively facing the rails 4 and 5 and supported thereby through interposed balls or rollers 7. In the carriage 6 a paper roller or platen 8 is mounted and provided with case shift mechanism, not shown, for shifting it up and down. The carriage 6 is drawn across the machine toward the left by means of a spring drum 10, band 11 and hook or bracket 12, this last secured to the carriage and having the band 11 connected therewith. The step-by-step feed of the carriage under the propulsion of the spring drum 10 is controlled by feed mechanism including a feed rack 13 mounted on the rear ends of arms 14, which arms are pivoted at 15 to the carriage 6, and are pressed downward by springs 16 into engagement with a feed pinion 17 mounted on the forward end of a shaft having one or more escapement wheels 18 mounted on the rear end 90 thereof. Two escapement wheels are here shown and they are controlled by a dog 20 mounted on a lever or dog rocker 21 which is connected by a link 22, arms 23 and rock shaft 24 with a universal bar 25 lying beneath the printing key levers 26. Said key levers have printing keys 27 mounted on their forward ends and they have their rear ends pivoted at 28 in the base of the machine, and they are provided with restoring 95

100

springs 29. These printing key levers, through means of links 30, sub-levers 31 and links 32, actuate front strike type bars 33 having types 34 mounted on their free ends and supported by a type bar segment 35.

5 The tabulator mechanism comprises a column stop bar 36 mounted on brackets 37 projecting rearward from the carriage 6. The bar 36 carries a series of column stops 10 38 for coöperation with denominational stops 40 consisting of the upper ends of a series of levers 41, which levers are pivoted at 42 in a frame 43 secured to the base 1 and the top plate 3 of the typewriter. The levers 41 are operated by push rods 44 pivoted to the lower ends of said levers and having denominational tabulator keys 45 at their forward ends, said rods being slidably mounted in a frame piece 46 and provided with returning springs 47. Each of said rods also has mounted thereon a collar or other adjustable push piece 48 and all of said collars or push pieces are so located as to operate a universal bar 50 mounted on arms 51 which are rigidly secured to a rock shaft 52 mounted in the base 1 of the machine. The arms 51 are connected by links 53 with arms 54 depending from a rock shaft 55 located in the rear part of the machine. Said rock shaft 55 also has a curved arm 56 mounted thereon and connected by a link 57 with a carriage release lever 58 which at its forward end lies beneath the feed rack 13, the construction being such that, when any of the keys 45 is operated, the lever 58 is rocked and raises the feed rack 13 out of the pinion 17, thus releasing the carriage from its escapement and leaving it free to run until it is arrested 40 by the operated one of the stops 40 intercepting one of the column stops 38. The said column stops can be made adjustable in various ways in order to provide for arresting the carriage at any desired letter 45 space position. In the present instance there is provided a full set of said stops 38, one stop for each letter space position, and said stops are slidably mounted on the bar 36, being ordinarily in a forward position on 50 said bar such that they are out of reach of the stops 40. Any one of said stops 38 can, however, be slid backward to operative position by means of a setting lever 60 which is pivoted at 61 in a suitable support on the top plate 3 and which is connected by means 55 of a link 62 with a key lever 63, here shown as being similar in most respects to the printing key levers 26 and having a stop set 60 key 64 mounted on its forward end. The key lever 63 is cut out at 65 to avoid operating the universal bar 25. The lever 60 stands in suitable relation to the denominational stops 40 and such that when the carriage is in any given letter space position 65 and the key 64 is operated, that one of the

column stops 38 will be moved to operative position which is adapted to arrest the type-writer carriage in that letter space position when the denominational stop 40, corresponding to the decimal point, is operated. 70 The stops 38 are restored to normal position by means which include a button 66 mounted on the frame 43 and controlling a certain cam device which need not be here particularly described, being well known in the 75 art.

The Wahl computer comprises an actuator 67 and a carriage 68 on which one or more totalizers can be adjustably mounted. These parts are here shown of the usual 80 Wahl construction. The actuator comprises a framework and some mechanism including a master wheel 70, a rock shaft 71 having a series of graduated arms 72 thereon, and means, including a series of levers 73, for 85 operating said arms 72. The levers 73 are operated by links 74 connected with the key levers 26 of the numeral keys, which numeral keys are arranged in the back one of the four rows of printing keys. 90

The carriage 68 is supported and guided near the center of the machine by certain rollers 75, some of which appear in Fig. 1 and one of which appears in Fig. 3. These rollers are supported by a main frame piece 9 76 which also constitutes the main frame piece of the actuator 67. Said frame piece 76 is supported from the top plate of the typewriter by means of brackets 77 to which brackets said frame piece is secured by 1 screws or bolts 78 and nuts 79.

The computer carriage 68 is connected with the typewriter carriage 6 by means of brackets or arms 80 secured to the typewriter carriage by screws 81 and connected 1 with the computer carriage through screws or bolts 82 threaded through the vertically disposed forward ends of the brackets 80 and secured in position by lock nuts 83. Each of the screws 82 passes through a slot 84 in an arm 85 secured to and projecting from the corresponding end of the carriage 68.

The parts thus far described are or may be of substantially the Remington-Wahl construction; and in fact, as far as my invention is concerned, they may be of any suitable construction, my invention not being limited in its application to this particular machine.

I have shown one totalizer 86 which, with one or two exceptions that will be mentioned, is identical in construction with the ordinary Wahl totalizer. Registering mechanism included in said totalizer is or may be identical with that used in the Wahl machine which includes a series of gears 87 adapted to be operated one at a time by the master wheel 70 and also a series of numeral wheels 88, Fig. 2, geared to said gears 87

and adapted to show through suitable sight openings in the casing of the totalizer.

The Wahl carriage 68 is in the form of a bar of a length to cover the extent of carriage travel. The cross section of said bar includes a dove-tail 90 and the side plates of the Wahl adding heads are made to fit this dove-tail in such a way that the adding head or totalizer can be slid lengthwise of the carriage. The adding head can be secured in any letter space position lengthwise of the carriage by means of a latch or detent 91, Fig. 3, engaging the teeth of a rack bar 92 which is secured to the front face of the carriage 68, the latch 91 being drawn downward into engagement with the rack by means of a spring 93. To release the totalizer from its securing means, said latch is lifted out of engagement with the rack by means of a lever arm 94 which, in the Wahl machine, is situated at the right-hand side of the totalizer and has its upper end bent off to form a sort of key. The latch 91 and the arm 94 are rigidly mounted on a rock shaft 95 pivoted at its ends in the side plates of the totalizer. I have added to the usual Wahl construction a second arm 96 at the left-hand end of the rock shaft 95 and have connected said two arms by means of a yoke-piece 97 extending substantially the width of the adding head. The motion of the parts under the impulse of the spring 93, is limited by means of a cross rod 98, Fig. 3.

The purpose of the changes just above mentioned is to enable me, when a tabulator key is operated, to release the adding head from the control of its detent 91 so that said adding head is free to move lengthwise of the carriage 68. As will appear more fully hereinafter, the adding head moves toward the right at the same time that the typewriter carriage is moving toward the left under the control of the tabulator.

The release of the adding head is effected by means of a lever arm 100 having an anti-friction roller 101 mounted on its free end in position to coöperate with the cross bar 97. This roller 101 is on a fore and aft axis and the lever arm is pivoted at 102 on a transverse horizontal pivot mounted in ears 103 bent up from a base 104 of sheet metal secured by a screw 105 to the top part of the frame 76 where said frame supports the rollers 75. To the rear of the pivot 102 the lever 100 is formed with a depending arm 106 to which is connected one end of a spring 107, the other end of which is connected with a transverse rock shaft 108. The free end of the lever arm 106 lies behind a roller 110 mounted on a pin 111 that connects two lever arms 112 (Figs. 3 and 4), which lever arms are secured by screws 113 to the rock shaft 108. Said rock shaft extends across the machine just back of the actuator 67 and, as is perhaps best shown in Figs. 1 and 2,

it is journaled at its ends in plates 114 secured as by screws 115 to the ends of the actuator.

Near its right-hand end the shaft 108 has an arm 116 mounted thereon and extending toward the rear, said arm being connected by a link 117 with an arm 118 fixed on the transverse rock shaft 52, which rock shaft is rigidly connected with the universal bar 50 of the tabulator. The construction is such that when one of the tabulator keys is operated, this bar 50 is moved toward the rear and the arm 118, link 117 and arm 116 are drawn downward, rocking the shaft 108 and the arms 112 toward the rear, and thus rocking the arm 100, 106 and depressing the bar 97 and lifting the latch 91 out of the rack 92, as shown in Fig. 3. It will thus be seen that the described mechanism releases the latch 91 from the rack 92 when a tabulator key is operated.

The adding head is moved toward the right when released as just described, by means of a bar 120 having its right-hand end 121 bent downward and adapted to lie against the left-hand face of the adding head when said adding head is moving through an adding zone. The bar 120 is mounted for sliding in a right and left-hand direction in a guiding tube or casing 122 mounted on a frame piece 123 (Fig. 3) and also in an ear 124 (Fig. 4) bent off from an arm 125 of said frame piece 123. It will be noted that the bar 120, frame piece 123, and arm 125 lie just above the carriage 68 and to the left of the position that is occupied by the adding head when said adding head is in coöperation with the master wheel. The right-hand end of the bar 120 is formed of approximately rectangular cross section and its left-hand end 126 is formed smaller and round, and a spring 127 surrounds this part 126 and is compressed between the ear 124 and the shoulder formed at the beginning of the rectangular part of the bar. The tension of this spring is exerted to press the bar toward the right. The construction is such that when a number is being written in an adding column, the adding head is secured to the carriage 68 by means of the latch 91 and moves toward the left with said carriage, forcing the bar 120 leftward with it and compressing the spring 127. When a tabulator key is operated to move the typewriter carriage into a new adding zone, the lever 100 releases the latch 91 and the spring 127 moves the bar 120 and the adding head 86 toward the right until they are arrested by means which will presently be described. The part 126 of the bar 120 has at its left-hand end a nut 128 to prevent the end of said bar from escaping from the ear 124. The frame piece 123 is supported by two posts 130, which posts project toward the front of the machine from a frame plate 131.

131 which in turn is secured to a plate 132 that extends across back of the actuator and is secured in position in any suitable manner. In the present instance this plate 132 lies between the main frame piece 76 of the actuator, and the brackets 77, being secured in position at each end by the bolt 78.

In order to arrest the bar 120 and the adding head 86 in harmony with the arrest 10 of the typewriter carriage, that is to say, in a position of the same denomination as that of the typewriter carriage, the bar 120 is cut away at its rear face to form a shoulder 133, and this shoulder, as the bar moves toward the right, is adapted to be arrested by any one of a series of denominational stops 134 consisting of the forward ends of push bars which are slidably mounted in suitable slots or holes 135 in the plate 132 and in 20 similar apertures in the bar or plate 131, said stops being situated a distance apart equal to a letter space interval of the carriage. The stops 134 are operatively connected with the denominational tabulator of 25 the typewriter. Such connections can of course be made in various ways but as here shown each of the bars 134 is pivoted at its rear end to a bell crank 136, a series of such bell cranks being pivoted on a rod 137, 30 which rod is mounted in lugs or brackets 138 projecting toward the rear from the frame plate 132. The bell cranks 136 are operated by push links 140 which pass downward from said bell cranks behind the actuator 35 and in front of the type bar basket and are pivoted at their lower ends to the forward ends of bell cranks 141, which in turn are pivoted on the rock shaft 52 of the tabulator. The bell cranks 141 are connected by links 40 142 extending rearward therefrom above the key levers 26, and each of said links 142 has at its rear end a pin 143 that projects therefrom into a slot 144 formed in one of the denominational stop levers 41. The construction is such that when this lever is 45 moved toward the rear of the machine by the operation of the corresponding key, it first moves free of the link 142, due to the lost motion in the slot 144, and then operates said link and the train of connections extending up to the stop 134, which stop is pushed toward the front of the machine 50 into contact with the bar 120 and into the path of the stop shoulder 133 on said bar. The bell cranks 141 pass forward through 55 the series of links 30, which series extends across the front of the machine, each of said bell cranks being so located as to go between two of these links without interfering with 60 said links.

In order to prevent overthrow of the adding head when it is moved toward the right by the spring 127 and the bar 120, means may be provided for coupling said adding head with said bar. To this end I have se-

cured a small hook 145, made of thin sheet metal, to the left-hand side of the adding head by means of a screw 146, this being one of the screws already employed in the Wahl machine for fastening the side plate of the 70 adding head to one of the cross bars. As here constructed and as will be understood from Figs. 3 and 5, this hook forms a shallow notch into which the depending end 121 of the bar 120 is adapted to engage. This 75 bar may engage said hook permanently if desired but preferably it is capable of moving out of engagement with the hook as shown in Fig. 5. As shown in this figure the bar 120 is not exactly of rectangular 80 cross section but on the contrary the angles of said bar are slightly oblique so that in resting on the casing or guiding tube 122 the free end 121 of the bar is held by gravity, as shown in Fig. 5, in a position where it does 85 not engage this hook 145. When, however, a tabulator key is operated, the operated one of the stops 134 moving into engagement with the flat rear face of the bar 120, rocks said bar into engagement with the hook, as 90 shown in Fig. 3.

In operation the machine is set for the particular piece of work in hand by setting to operative position suitable ones of the column stops 38, this being done in the machine shown by moving the typewriter carriage to the position in each adding column corresponding to the decimal point and operating the stop-set key 64. If, for example, there are to be five numbers on a line, all 95 of which are to be registered on the totalizer 86, then five of these stops 38 will be set to operative position, and these may, for example, be the stops corresponding to the letter space positions 30, 40, 50, 60 and 70 100 of the typewriter scale; or they may be in other positions, depending upon the manner in which it is desired to arrange the numbers on the sheet of paper. When the paper is inserted in the machine and the typewriter 110 carriage is drawn back toward the right to begin a line of writing, which line includes some of the numbers to be added, the totalizer will be moved to the right with said carriage. Matter other than said numbers 115 can be written at the first part of the line if necessary, or for that matter, at any part of the line. When he is ready to begin the writing of numbers to be registered, the operator, by manipulating the cross bar 97, 120 releases the adding head from the bar 68 and moves it toward the left as far as it will go, which is to the position shown in Figs. 2 and 4. The tabulator is then operated, such operation consisting in pushing 125 one of the keys 45 toward the rear. This key operates the corresponding one of the denominational stops 40 of the typewriter and of the stops 134 of the computer. The key also, through the universal bar 50 and 130

the described connections, releases the typewriter carriage from its escapement and also releases the adding head 86 from its carriage 68. The typewriter carriage then 5 runs to the left under the impulse of the spring drum 10 until it is arrested by the denominational stops 38 and 40, and the adding head moves toward the right under the impulse of the spring 127 until it is arrested by the shoulder 133 and the operated one of the stops 134. If, for example, the first digit of the number to be added is of the hundreds denomination, then both the typewriter carriage and the adding head 10 will be arrested in the hundreds position; that is to say, in the position for writing hundreds on the typewriter and in the position where the master wheel 70 is in engagement with the hundreds gear 87. When the 15 tabulator key is released and the typewriter carriage is restored to the control of its escapement, the stop 40 is withdrawn out of the path of the stop 38, the lever 100 rises, allowing the latch 91 to move into engagement with the rack 92 and the stop 134 is withdrawn, leaving the adding head coupled to the computer carriage. As the number 20 is written and the typewriter and computer carriages are stepped toward the left, they carry the adding head with them until the last digit of said number is written and registered, when said adding head will be found in its normal or initial position shown in Figs. 2 and 4. The tabulator is then again 25 operated, bringing the typewriter carriage to the proper denominational position in the second column and again moving the adding head toward the right to the same denominational relation with the master wheel. 30 This operation is repeated until all of the numbers in that line have been written and added, whereupon the typewriter carriage is again drawn toward the right and the paper is line spaced. Before registering 35 the numbers written in the next line, it is necessary to move the adding head to the left again by hand into its initial position. It will be noted that when one of the 40 column stops 38 has been set to operative position, the setting of this stop automatically predetermines which one of the notches in the rack 92 will be engaged by the detent 91. In other words, the setting of one of the stops 38 predetermines the exact position 45 at which the adding head will be connected with the carriage 68 every time the typewriter carriage is arrested by said stop 38. This position on the carriage 68 and this notch in the rack 92, will be the same 50 whichever one of the tabulator keys is operated. In the present instance only five of such keys are shown connected up. If the one of these keys of highest denomination, namely, in the present instance, the key 55 marked "1,000", is operated, then the type-

writer carriage will be moved its least distance toward the left and the adding head will be moved its greatest distance toward the right for this particular setting of the tabulator mechanism, and the adding head 70 will be brought to a certain position on the carriage 68. If with the same setting of the stops 38 the units tabulator key be operated, then the typewriter carriage will move to its greatest distance toward the left and the adding head will be moved its least distance toward the right, with the result that the adding head will come to the same identical position on the carriage 68 as before. Said carriage 68 will have moved four spaces 80 farther toward the left in the second instance than in the first but the adding head will also be four spaces toward the left by reason of the fact that it has moved four spaces less toward the right. It will be 85 seen, therefore, that I have provided means for automatically coupling the adding head to the computer carriage at a series of points in each line of writing, that each of these points can be located at any letter space position desired, and that the only operation necessary to determine these points is to set the appropriate stops 38 of the typewriter tabulator. The construction is such, therefore, that the operator has only to see 90 to it that the adding head is always under the control of the bar 120, as has been described in detail hereinbefore, and has only to work the typewriter including its tabulator mechanism in the ordinary way and 100 the computer mechanism will adapt itself automatically to the setting and operation of the typewriter mechanism. The operator is thus relieved of any necessity for keeping the typewriting and computing mechanisms 105 set in harmony with each other.

It will be noted that, as here shown and described, my improvements consist almost entirely of attachments to the Remington-Wahl machine as it has heretofore been 110 manufactured. For example, the shaft 108 is pivoted in plates provided for the purpose and attached to the actuator; and the bar 120 and the tabulator stops 134 and their connections are mounted on a special plate 115 132. It will of course be understood that all of these parts can be built in as integral parts of the machine instead of being put on as attachments in the manner described, in which case the levers 130 and the bar 120 120 and the other neighboring parts of my mechanism, would probably be supported from the frame piece 76 instead of from a special part like the plate 132.

Some of the features of my invention are 125 applicable to machines in which the traveling element of the computer derives its traveling motion from some other source than the typewriter carriage.

It will also be understood that various 130

other changes can be made in the details of construction and arrangement without departing from my invention.

What I claim as new and desire to secure 5 by Letters Patent, is:-

1. In a combined typewriting and computing machine, the combination of a traveling typewriter carriage, computing mechanism comprising as elements thereof a totalizer and a master means for operating said totalizer in one denomination after another, means whereby one of said elements can be coupled to said typewriter carriage at different letter space positions, denominational 10 tabulator mechanism for the typewriter carriage including column stop devices adjustable to locate the decimal point at different letter space positions, means controlled by said tabulator for releasing said coupling 15 means to free from the typewriter carriage said element that was coupled thereto, a spring for moving said element when so freed in a direction contrary to that in which it is moved by the carriage travel, and denominational stops for arresting the motion 20 of said element under the impulse of said spring in a position of the same denomination as that in which said carriage is arrested by its tabulator.
2. In a combined typewriting and computing machine, the combination of typewriting mechanism including a traveling carriage; computing mechanism including as elements thereof a totalizer and a master 25 means; means for coupling one of said elements to said carriage at different positions; a set of denominational tabulator keys; means controlled by said keys for releasing 30 said coupling means; separate sets of denominational stops controlled by said keys, one set of stops for arresting the typewriter carriage and the other set of stops for arresting 35 said element; and a spring for moving said element till arrested by the operated 40 one of its said stops.
3. In a combined typewriting and computing machine, the combination of a typewriter carriage, denominational tabulator mechanism for said carriage including adjustable column stops, a computer carriage, 45 a totalizer mounted on said computer carriage, means for coupling said totalizer to said computer carriage at different points letter space distances apart, means operated 50 by said tabulator mechanism for releasing said coupling means, and means for sliding said totalizer along on said carriage and re-coupling it to said carriage in a letter space 55 position in harmony with that of a column stop of said tabulator.

4. In a combined typewriting and computing machine, the combination of a typewriter carriage, denominational tabulator mechanism for said carriage, a computer carriage traveling in harmony with said

typewriter carriage, a totalizer mounted on said computer carriage, a rack on said computer carriage spaced in accordance with the letter spacing intervals of carriage travel, means for coupling said totalizer 70 directly to said rack at different letter space positions, and means operated by said tabulating mechanism for releasing said totalizer from said rack when said tabulator mechanism is operated.

75

5. In a combined typewriting and computing machine, the combination of a typewriter carriage, denominational tabulator mechanism for said carriage, a rack traveling in unison with said typewriter carriage, 80 a totalizer having a latch for engagement with the teeth of said rack whereby said totalizer can be coupled up with said typewriter carriage at different letter space positions, and means controlled by the said 85 tabulator mechanism for coupling said totalizer by means of said latch with said rack in positions determined by the column stop or stops of said tabulator mechanism.

90

6. In a combined typewriting and computing machine, the combination of a typewriter carriage, a bar whose length covers the extent of the carriage travel, a totalizer mounted on said bar and movable relative thereto in the direction of the length of 95 said bar, means for coupling said totalizer to said bar at points letter space distances apart, means for operating said totalizer to register numbers, and means for automatically uncoupling said totalizer from said bar, re-locating it and re-coupling it to said bar at a new point as the typewriter carriage is positioned to write a new number on the same line of writing as a preceding number, whereby a series of numbers written in a line across the paper are automatically 100 registered on said totalizer.

100

7. In a combined typewriting and computing machine, the combination of a typewriter carriage, a bar whose length covers 110 the extent of carriage travel, a totalizer mounted on said bar and movable relative thereto in the direction of the length of said bar, means for coupling said totalizer to said bar at points letter space distances apart, means for operating said totalizer to register numbers, denominational tabulator mechanism for positioning said typewriter carriage for writing a series of numbers in 115 a line across the paper, and means controlled by said tabulator for uncoupling said totalizer, re-locating it on said bar, and re-coupling it to said bar at the new location, whereby a series of numbers written in a line across the paper are automatically 120 registered on said totalizer.

115

8. In a combined typewriting and computing machine, the combination of a typewriter carriage, a computer carriage traveling in unison with said typewriter carriage, 130

125

a totalizer, means for coupling said totalizer to said computer carriage at different points letter space distances apart, tabulator mechanism, means operated by said tabulator mechanism for releasing said coupling means, a spring pressed device in the path of travel of said totalizer and adapted to be displaced as said totalizer travels through a computing zone, and denominational stop devices operated by said tabulator mechanism for arresting said spring-pressed devices in different denominational positions.

9. In a combined typewriting and computing machine, the combination of a typewriter carriage, a computer carriage traveling in unison with said typewriter carriage, a totalizer, means for coupling said totalizer to said computer carriage at different points letter space distances apart, tabulator mechanism, means operated by said tabulator mechanism for releasing said coupling means, a spring-pressed device in the path of travel of said totalizer and adapted to be displaced as said totalizer travels through a computing zone, denominational stop devices operated by said tabulator mechanism for arresting said spring-pressed device in different denominational positions, and means for coupling said spring-pressed device to said totalizer.

10. In a combined typewriting and computing machine, the combination of a typewriter carriage, computing mechanism including as elements thereof a totalizer and a master means, means for coupling one of said elements to travel in unison with said typewriter carriage, tabulator mechanism comprising a carriage release device for the typewriter and means for uncoupling said coupling means, and said tabulator mechanism also comprising two sets of denominational stop devices, one of said sets of stop devices adapted to arrest the typewriter carriage in a selected denominational position when traveling in one direction and the other of said sets of stop devices adapted to arrest said coupled element at the same denominational position when traveling in the opposite direction, and a spring for moving said element in said opposite direction when uncoupled from the typewriter carriage.

11. In a combined typewriting and computing machine, the combination of a traveling typewriter paper carriage, a traveling computer carriage, a totalizer adjustably mounted on said computer carriage, a spring-pressed bar or plunger in the path of travel of said totalizer adapted to be moved against the tension of its spring by the travel of said totalizer, and key-operated means for releasing said totalizer to be moved by said spring in a direction contrary to that of its travel and for arresting said totalizer in selected denominational positions.

12. In a combined typewriting and computing machine, the combination of a traveling typewriter carriage, computing mechanism including as elements thereof a totalizer and a master means, means for causing one of said elements to travel in unison with the travel of the typewriter carriage, means for freeing said element from said carriage, a spring for moving said element in a direction contrary to that of its travel, and denominational stop devices for arresting the motion of said element under the impulse of said spring in different selected denominational positions.

13. In a combined typewriting and computing machine, the combination of a typewriter carriage, computing mechanism including as elements thereof a totalizer and a master means, means for causing one of said elements to travel in unison with the travel of said typewriter carriage, means for freeing said element from said carriage, a spring-pressed bar or plunger for moving said element in a direction contrary to that of its travel, and a series of denominational stops coöperating with said bar or plunger to arrest it in different selected denominational positions.

14. In a combined typewriting and computing machine, the combination of a typewriter carriage, adjustable column stops, a series of separately operable denominational stops for coöperating with said column stops to arrest the typewriter carriage in different selected denominational positions and in different columns, a totalizer movable in unison with said carriage, a separate set of separately operable denominational stops for said totalizer, denominational tabulator keys, each key connected with one of the denominational stops of each of said sets, a driving spring for said typewriter carriage, a second driving spring for said totalizer, and means operated by said tabulator keys for separately releasing said typewriter carriage and said totalizer to the action of their respective springs.

15. In a combined typewriting and computing machine, the combination of a typewriter carriage, a computer carriage at the front of the machine, a totalizer mounted on and capable of being moved lengthwise of said computer carriage, means adjacent said computer carriage for moving said totalizer lengthwise of said computer carriage, and independently of said typewriter carriage, and a series of denominational stops for arresting said totalizer and its said moving means.

16. In a combined typewriting and computing machine, the combination with typewriting mechanism, of a computer carriage, a totalizer mounted on said carriage and capable of being moved lengthwise of said carriage, means for securing said totalizer in

different adjusted positions lengthwise of said carriage, and special denominational stop devices for arresting said totalizer when freed from said securing means.

5 17. In a combined typewriting and computing machine, the combination with typewriting mechanism, of a computer carriage, a totalizer traveling with and adjustable along said carriage, a latch for securing said 10 totalizer in adjusted position on said carriage, means including a yoke-bar for releasing said latch, and tabulator mechanism for controlling the position of said totalizer on said carriage, said mechanism including a 15 releasing device adapted to operate said yoke-bar when the tabulator is operated.

18. In a combined typewriting and computing machine, the combination with typewriting mechanism, of a computer carriage, 20 a totalizer mounted on said carriage and capable of traveling with said carriage an extent materially in excess of the width of a computing zone, and denominational tabulator mechanism for positioning said totalizer 25 on said carriage in a plurality of different positions so that numbers written in different places along a line of writing can be automatically registered on said totalizer.

19. In a combined typewriting and computing machine, the combination of a typewriter carriage, adjustable column stops at the rear of said carriage, denominational tabulator stops for coöperating with said column stops, keys at the front of the machine for operating said denominational stops, a computer carriage at the front of the machine, denominational stops connected with said keys and situated adjacent to said computer carriage, a totalizer mounted 40 on said computer carriage, and means for moving said totalizer independently of said computer carriage to positions determined by said forward denominational stops whereby said totalizer can be located on said 45 computer carriage a plurality of times in the course of writing a single line on the typewriter.

20. In a combined typewriting and computing machine, the combination of a typewriter carriage, adjustable column stops at the rear of said carriage, denominational stop levers for coöperation with said column stops, denominational tabulator keys for operating said column stops, a computer carriage at the front of the machine, a totalizer 55 adjustably mounted on said computer carriage, denominational stops adjacent said carriage, a spring-pressed device controlled by said denominational stops and adapted to 60 act on said totalizer, means for securing said totalizer in adjusted position on said carriage, a release device for said securing means operative by said tabulator keys, and

links and levers connecting said forward denominational stops with said tabulator keys. 65

21. In a computing machine, the combination of a traveling carriage; a totalizer; means for operating said totalizer; means for coupling said totalizer to said carriage at different points; a spring put under tension by the travel of said totalizer with said carriage; means for releasing said totalizer from said carriage to the action of said spring, and means which does not partake of the travel of said carriage for arresting 75 the motion of said totalizer under the impulse of said spring in selected denominational positions; whereby said totalizer can be operated a plurality of times in a single run of said carriage. 80

22. In a computing machine, the combination with a totalizer and a master means constituting elements of said computing machine, of a traveling carriage; means for coupling one of said elements to said carriage; a spring put under tension by the travel of said element with said carriage; means for releasing said element from said carriage to the action of said spring, and means which does not partake of the travel 85 of said carriage for arresting the motion of said element under the impulse of said spring in selected denominational positions; whereby said totalizer can be operated a plurality of times in a single run of said 90 carriage. 95

23. In a computing machine, the combination of a totalizer, master means for operating said totalizer, a traveling carriage, a coupling device for coupling said totalizer 100 to said carriage, a bar on said totalizer, a lever for acting on said bar to release said coupling means, and means for causing said totalizer to be moved to a new position on said carriage and into a selected denominational position with reference to said master means. 105

24. In a computing machine, the combination with a totalizer and a master means constituting elements of said computing machine, of a shouldered, spring-pressed bar, means for causing one of said elements to travel with relation to another and to move said bar against the tension of its spring; means for releasing said element to the action of said spring-pressed bar; and denominational stops coöperative with said shoulder. 110 115

25. In a combined typewriting and computing machine, the combination with typewriting mechanism and computing mechanism, said computing mechanism including as elements thereof a totalizer and a master means, of means for imparting a traveling motion to one of said elements with respect 120 to the other, a spring put under tension by 125

such traveling motion, means for releasing said element to the action of said spring, and means which does not partake of the travel of said carriage for arresting the motion of said element under the impulse of said spring in selected denominational positions.

26. In a combined typewriting and computing machine, the combination with typewriting mechanism and computing mechanism, said computing mechanism including as elements thereof a totalizer and a master means, of means for imparting a step by step travel to one of said elements, a spring-pressed bar or plunger moved by said step-by-step motion to put the spring under tension, means for releasing said element to the action of said spring-pressed bar or plunger, and a series of denominational stops for arresting said bar or plunger in selected denominational positions.

27. In a combined typewriting and computing machine, the combination with typewriting mechanism and computing mechanism including a relatively stationary master means, a traveling totalizer, and means for imparting a step-by-step travel to said totalizer, of a spring put under tension by such travel of said totalizer, a series of denominational keys, means operated by all of said keys for releasing said totalizer to the action of said spring, and a series of denominational stops one connected with each of said keys for arresting said totalizer in selected denominational positions.

28. In a combined typewriting and computing machine, the combination of typewriting mechanism including a traveling paper carriage, computing mechanism including a computer carriage at the front of the machine, a totalizer mounted on and traveling with said computer carriage, a master means, denominational tabulator mechanism for the typewriter carriage including a series of stop levers at the back of the machine and means for operating said levers, links extending from said levers toward the front of the machine, bell-crank operated by said links, a series of denominational stops adjacent said computer carriage, connections from said bell-crank to the last mentioned denominational stops, and means for releasing said totalizer from said computer carriage and for moving it into engagement with one of the last mentioned denominational stops.

29. In a combined typewriting and computing machine, the combination of a typewriter carriage, a traveling totalizer, a spring for restoring said totalizer, a series of denominational tabulator keys, and two series of denominational stops operated by said keys, one series of said stops coöper-

ating with the typewriter carriage and the other series with the said traveling totalizer. 65

30. In a computing machine, the combination of a traveling carriage, a totalizer adjustably mounted on said carriage, means for operating said totalizer, a device for moving said totalizer with relation to said carriage, denominational stop mechanism co-operating with said device to control selectively the denominational position to which said totalizer is moved, and means whereby an operation of said denominational stop mechanism causes said device to be coupled to said totalizer. 75

31. In a computing machine, the combination of a traveling carriage, a totalizer adjustably mounted on said carriage, means for operating said totalizer, and means for readjusting said totalizer on said carriage, said readjusting means comprising a slide bar, means for moving said slide bar to a selected denominational position, and means for temporarily coupling said slide bar to said totalizer. 80

32. In a computing machine, the combination of a traveling carriage, a totalizer adjustably mounted on said carriage, means for operating said totalizer, and means for readjusting said totalizer on said carriage, said readjusting means comprising a sliding bar, a series of denominational stops for co-operation with said bar, means whereby said stops when operated rock said bar, and means whereby said bar when so rocked is coupled to said totalizer. 95

33. In a combined typewriting and computing machine, the combination of a typewriter carriage, tabulator mechanism comprising a series of denominational stops and a series of column stops for arresting said typewriter carriage in different denominational positions and in different columns, a totalizer, means for coupling said totalizer to travel with said typewriter carriage, a spring-pressed bar moved against the tension of its spring by such travel of said totalizer, means for releasing said coupling means, denominational stops coöperating with said bar, said stops when operated being pressed against said bar and thereby rocking said bar and coupling it to said totalizer, lost motion connection between the denominational stops of the typewriter and the denominational stops for the totalizer, and means for operating said denominational stops. 100

34. In a combined typewriting and computing machine, the combination of a typewriter carriage, a toothed rack traveling in unison with said carriage, a totalizer having a latch for engagement with the teeth of said rack whereby said totalizer can be coupled up with said typewriter carriage at 105 110 115 120 125

different positions letter space distances apart; a spring tending to move said totalizer in a direction contrary to the direction of carriage travel, and means for releasing 5 said latch, allowing said totalizer to be moved by said spring and reconnecting said latch with said rack teeth at another and predetermined letter space position.

Signed at Amsterdam, in the Province of Noord, the Netherlands, this 11th day of 10 April, A. D. 1913.

LEENDERT PIETER POLHUIS.
